(57) CLAIM

The ornamental design for a bouquet holder and stand, as shown and described.

DESCRIPTION

FIG. 1 is a perspective view of a bouquet holder and stand showing my new design;

FIG. 2 is a front view thereof;

FIG. 3 is a rear view thereof;

FIG. 4 is a side view thereof, the opposite side being identical thereto;

FIG. 5 is a top plan view thereof;

FIG. 6 is a bottom plan view thereof;

FIG. 7 is a top plan view of an alternate form of the "bouquet holder and stand" showing my new design;

FIG. 8 is a top plan view of another alternate form of the "bouquet holder and stand" showing my new design; and,

FIG. 9 is a top plan view of yet another alternate form of the "bouquet holder and stand" showing my new design.
